UNITED STATES PATENT OFFICE

163,103

PLANTER OR THE LIKE

Millesan Drews, Los Angeles, Calif.

Application August 16, 1949, Serial No. 4,522

Term of patent 14 years

(Cl. D35—3)

To all whom it may concern:

Be it known that I, Millesan Drews, a citizen of the United States, residing at Los Angeles, in the county of Los Angeles, State of California, have invented a new, original, and ornamental Design for Planter or the like, of which the following is a specification, reference being had to the accompanying drawing forming a part thereof.

I claim:

The ornamental design for a planter or the like, as shown.

MILLESAN DREWS.
